United States Patent Office

Des. 192,832
Patented May 15, 1962

192,832

WATER SLED OR SIMILAR ARTICLE

Arthur E. Forseth, Halstad, Minn.

Filed Dec. 4, 1961, Ser. No. 67,781

Term of patent 7 years

(Cl. D71—1)

FIG. 1

FIG. 2

FIG. 3

FIG. 4

FIG. 5

FIGURE 1 is a view in top plan of a water sled or similar article showing my new design;

FIG. 2 is a view in bottom plan;

FIG. 3 is a view in elevation showing one side, the other side being identical;

FIG. 4 is a view in front elevation; and

FIG. 5 is a view in rear elevation.

I claim:

The ornamental design for a water sled or similar article, as shown and described.
